United States Patent Office

Des. 214,824
Patented Aug. 5, 1969

214,824

HELMET AND SLIDABLE VISOR

John Fisher, Dover, Del., assignor to ILC Industries, Inc.,
Dover, Del., a corporation of Delaware

Filed Mar. 29, 1968, Ser. No. 11,206

Term of patent 14 years

Int. Cl. D2—03

U.S. Cl. D2—252

FIG-1

FIG-3

FIG-2

FIG-4

FIG. 1 is a front elevational view of a helmet showing my new design;

FIG. 2 is a side elevational view thereof;

FIG. 3 is a front elevational view thereof with the face shield portion in an above the face position on the helmet; and

FIG. 4 is a side elevational view thereof.

The face shield portion of the helmet has been shaded for transparency.

I claim:

The ornamental design for a helmet and slidable visor as shown and described.
